[57] CLAIM

The ornamental design for an archer's bow holder,
 substantially as shown.

DESCRIPTION

FIG. 1 is a perspective view of an archer's bow holder
 embodying our new design;
 FIG. 2 is a left side elevational view thereof;
 FIG. 3 is a top plan view thereof;
 FIG. 4 is a right side elevational thereof;
 FIG. 5 is a front elevational view thereof;
 FIG. 6 is a rear elevational view thereof; and
 FIG. 7 is a bottom plan view thereof.
